CLAIM

We claim the ornamental design for the spray mister and fan combination, as shown and described.

DESCRIPTION

FIG. 1 is a perspective view of the spray mister and fan combination showing our new design;

FIG. 2 is a front elevational view thereof;

FIG. 3 is a right side elevational view thereof;

FIG. 4 is a left side elevational view thereof;

FIG. 5 is a rear elevational view thereof;

FIG. 6 is a top plan view thereof; and,

FIG. 7 is a bottom plan view thereof.

The element shown in broken lines on the upper portion of FIGS. 1, 2 and 5 is for illustrative purposes only; and forms no part of the claimed design.
